DESIGN FOR A SHOEbrush

Albert Racicot, Aurora, Ill., assignor to National Brush Company, Aurora, Ill., a corporation of Illinois

Application April 5, 1941, Serial No. 100,169

Term of patent 14 years

To all whom it may concern:

Be it known that I, Albert Racicot, a citizen of the United States, residing at Aurora, in the county of Kane and State of Illinois, have invented a new, original, and ornamental Design for a Shoebrush, of which the following is a specification, reference being had to the accompanying drawing, forming part thereof, in which:

Figure 1 is a perspective view of a shoebrush
showing my new design;

Figure 2 is a side elevational view thereof; and Figure 3 is a front elevational view thereof.
I claim:

The ornamental design for a shoebrush, substantially as shown.

ALBERT RACICOT.
